UNITED STATES PATENT OFFICE

JOHN J. DALY, OF WEST NEWTON, MASSACHUSETTS

DESIGN FOR A STORE FRONT

Application filed September 24, 1930. Serial No. 37,064. Term of patent 14 years.

To all whom it may concern:

Be it known that I, JOHN J. DALY, a citizen of the United States, residing at West Newton, in the county of Middlesex and Commonwealth of Massachusetts, have invented a new, original, and ornamental Design for Store Front, of which the following is a specification, reference being had to the accompanying drawings, forming part thereof.

Fig. 1 is a front view of a store front showing my new design.

Fig. 2 is a fragmentary interior view in side elevation, partly in section and on the line 2—2 of Fig. 4.

Fig. 3 is a fragmentary view partly in section and partly in side elevation and as seen from a point at the entrance to the store, on the line 3—3 of Fig. 4.

Fig. 4 is a fragmentary top plan view in diagrammatic outline and on a somewhat reduced scale, and

Fig. 5 is a view looking into the store and showing those portions of the show case both without and within the store.

I claim:

The ornamental design for a store front as shown.

JOHN J. DALY.
